United States Patent

Des. 235,421
Patented June 17, 1975

235,421

WRIST WATCH

Nicholas G. Pitrelli, 97—48 107th St.,
Ozone Park, Long Island, N.Y. 11416

Filed May 11, 1973, Ser. No. 359,556

Term of patent 14 years

Int. Cl. D10—02

U.S. Cl. D10—39

FIG. 1.

FIG. 2.

FIG. 1 is a top plan view of a wrist watch showing my new design.

FIG. 2 is a front side elevational view thereof.

The rear of the wrist watch is conventionally plain and unornamented.

I claim:

The ornamental design for a wrist watch, substantially as shown and described.
